CLAIM

The ornamental design for an beach shade, as shown and described.

DESCRIPTION

FIG. 1 is a top, rear and right perspective view of the beach shade showing my new design;

FIG. 2 is a perspective view of its bottom, front and right sides;

FIG. 3 is its front view;

FIG. 4 is its rear view;

FIG. 5 is its left view;

FIG. 6 is its right view;

FIG. 7 is its top view;

FIG. 8 is its bottom view

FIG. 9 is an enlarged view of part 9 shown in FIG. 1;

FIG. 10 is an enlarged view of portion 10 shown in FIG. 1;

FIG. 11 is an enlarged view of portion 11 shown in FIG. 1;

FIG. 12 is an enlarged view of part 12 shown in FIG. 1;

FIG. 13 is an enlarged view of portion 13 shown in FIG. 2;

FIG. 14 is an enlarged view of portion 14 shown in FIG. 2;

and,

FIG. 15 is an enlarged view of portion 15 shown in FIG. 2.
